Attorney.

UNITED STATES PATENT OFFICE.

WILLY KUNZE, OF BREMEN, GERMANY.

DIAPHRAGM FOR SUBMARINE SIGNAL TRANSMITTERS.

Application filed July 19, 1920. Serial No. 397,546.

To all whom it may concern:

Be it known that I, Dr. WILLY KUNZE, a citizen of the German Republic, and a resident of Bremen, Germany, have invented 5 certain new and useful Improvements in Diaphragms for Submarine Signal Transmitters (for which an application has been filed in Germany on July 20, 1918, by the firm Atlas Werke A. G., of Bremen, Germany, with my knowledge and consent), of which the following is a specification.

It is usual, to arrange on board of ships the submarine signal transmitters within special chambers, which are filled with 15 water. In submarine boats these transmitters are arranged within the front flooding tanks. As however the transmitter diaphragms usually have a diameter exceeding half of a meter, the arrangement resulted 20 in extraordinary difficulties and accordingly it is an urgent requirement, to keep the diameter of these diaphragms as small as possible. The transmitter casing proper mostly has a smaller diameter than the diaphragm itself. 25 On the other hand at a given or required amount of the sound energy, delivered to the water, and of the sound softening, it will not be advisable to diminish the diameter of the diaphragm below a certain limit, without 30 straining the material too much. As for signaling relatively high sounds are employed, overtones of the diaphragm are utilized for the tuning of the oscillating system. Thereby in the diaphragm node circles 35 are formed, in which the oscillating or swinging amplitude is zero.

According to the invention the rim zone of the diaphragm is bent off inwardly in such a manner, that the circle, in which the 40 diaphragm is secured to the casing, has a smaller diameter than the diaphragm itself. It will be advisable in this connection to choose the point at which the diaphragm shall be bent in conformity to a node circle. 45 By this arrangement the diameter of the diaphragm is substantially diminished, without that the oscillating or swinging relations are materially changed. As the bending of the diaphragm would cause difficulties, in practice the desired shape is given to the diaphragm already while casting or turning the same.

In the accompanying drawing, illustrating the subject matter of my invention in a diagrammatical manner,

Fig. 1 shows the diaphragm in use until now, the shape of the same being thus selected, that a system of swinging or oscillating as represented by the dotted lines, is produced.

A_1 and A_2 are points of the node circle. For the purpose of securing the diaphragm the flange F of the casing G is employed. The force acts in the direction of the arrows.

In Fig. 2 the diaphragm is bent off at A_1 65 and A_2 according to the principle of the invention and the diameter of the diaphragm is thereby reduced for about one third of the previous diameter.

According to the present invention the 70 diaphragm consists of a substantial flat plate and an inward flange which serves to secure the diaphragm to the body of the transmitter by means of bolts and the like. Plate and inward bent flange may be two 75 separate members but preferably both parts will constitute one single piece of cast or turned iron, steel or bronze. This construction allows the diameter of the fastening periphery to be much smaller than the outer 80 diameter the diaphragm and using the inward bent flange for helping to produce the sound. This effect is more particularly obtained if the inward bent flange begins in the neighborhood of the node circle of the 85 overtone of the diaphragm.

The transmitter G to be used in connection with the diaphragm may be that of the normal electrical type comprising means oscillating by the effect of an alternating current. 90 These oscillations of the members of the transmitter act by means of a rod upon the centre of the plate which for this purpose shows here a small enlargement as indicated by the drawing.

Having thus particularly described the nature of my invention, what I claim as new and desire to secure by Letters Patent of the United States is:

1. Diaphragm for submarine signal transmitters comprising a substantial flat plate and an inward bent flange, the inward periphery of said flange being of smaller diameter than the outer diameter of the plate and

serving for securing the diaphragm to the transmitter body.

2. Diaphragm for submarine signal transmitters comprising a substantial flat plate and an inward bent flange, both members being made in one piece.

3. Diaphragm for submarine transmitters

comprising a flat plate and an inward bent flange, said flange beginning at the point where a node point would be, if the diaphragm would be stretched out flat.

In testimony whereof I affix my signature.

DR. WILLY KUNZE.
